UNITED STATES PATENT OFFICE.

WILLIAM A. PENFIELD, OF MERIDEN, CONNECTICUT, ASSIGNOR TO THE
BRADLEY & HUBBARD MFG. CO., OF SAME PLACE.

ACETYLENE-GAS BICYCLE-LAMP.

SPECIFICATION forming part of Letters Patent No. 664,775, dated December 25, 1900.

Application filed December 11, 1899. Serial No. 739,861. (No model.)

To all whom it may concern:

Be it known that I, WILLIAM A. PENFIELD, of Meriden, in the county of New Haven and State of Connecticut, have invented a new Improvement in Acetylene-Gas Bicycle-Lamps; and I do hereby declare the following, when taken in connection with the accompanying drawings and the letters of reference marked thereon, to be a full, clear, and exact description of the same, and which said drawings constitute part of this specification, and represent, in—

Figure 1, a view in vertical central section of an acetylene-gas bicycle-lamp constructed in accordance with my invention; Fig. 2, a plan view of the water-tank, showing the filler in its closed position; Fig. 3, a corresponding view showing the filler in its open position; Fig. 4, a perspective view of the top 20 of the tank with its adjuncts removed; Fig. 5, an enlarged sectional view of the water-feeding plug; Fig. 6, a detached view thereof, in side elevation, looking toward one end of its double-ended water-discharge passage.

25 My invention relates to an improvement in acetylene-gas bicycle-lamps, the object being to provide therefor simple, convenient, and reliable devices for filling the water-tank and for feeding the water therefrom into the carbid-receptacle.

With these ends in view my invention consists in certain details of construction and combinations of parts, as will be hereinafter described, and pointed out in the claims.

35 In carrying out my invention as herein shown I provide the water-tank A with a circular filler-opening A', formed in its integral top A², in which a hub B is centrally located, the said hub being formed at its lower end with 40 a flange B' and at its upper end with a flange B'. The filler-opening A' is closed by an elastic filler-cap C, consisting of a disk of rubber or other equivalent material secured to a button D, smaller in diameter than

45 the cap and also smaller in diameter than the opening A', and provided upon its lower face with a heavy rivet d, by means of which the cap is held in place, and upon its upper face with a small rivet d', by means of which 50 the button is secured to a horizontally swinging and vertically tilting arm E, swiveled

upon the hub B before mentioned. This arm is provided at its outer end with a finger-piece E' and at its opposite end with an integral spring E², which rides upon a long segmental tension-cam F, located upon the integral top A² of the tank. To expose the filler-opening A' for filling the tank A, the arm E is engaged through its finger-piece E' and pushed to one side, so as to slide the cap 60 C away from the opening. At this time the spring E² rides down the cam F. On the other hand, to close the opening the arm is engaged through its finger-piece E' and swung in the opposite direction until the cap has 65 been registered with the opening. At this time the spring E² rides up the cam F and operates to tilt or rock the arm so as to cause the elastic cap C to be forced partially into the opening under the action of the button 70 D. By these means I am enabled to open and close the filler-opening very rapidly and very much more conveniently than by the use of a screw-threaded filler-cap, which is very liable to get lost, particularly in the jarring 75 to which an acetylene-gas bicycle-lamp is exposed in use.

The hub B affords a bearing for the stem G, which is provided at its lower end with a tapering valve H and at its upper end with 80 an operating-button I, formed with a head I', between which and the flange B² of the hub B a spring J is interposed, this spring exerting a constant effort to lift the stem G. The valve H is entered into a water-feeding plug 85 K, mounted in the center of a diaphragm L, which separates the water-tank from the gas-generating chamber M of the lamp, the said tank and chamber being formed integral with each other. The said plug K is formed with 90 a tapered opening K', which receives the valve H and which merges into a small straight opening K², which in turn intersects a transversely-arranged double-ended discharge-opening K³, from which the water which is fed 95 through the plug is laterally discharged in both directions, the opposite sides of the plug being cut away, as at K⁴ K⁴, to facilitate this discharge. The said plug consists of a solid piece of metal in which the tapered opening 100 K', the opening K², and the discharge-opening K³ are formed. The extreme lower end

• K⁵ of the plug forms under this construction a guard to prevent its discharge - openings from being fouled and stopped—as, for instance, by the lifting of the cloth or gauze 5 which is generally placed over the carbid which is located in a carbid - receptacle N, which is inserted into the gas - generating chamber, through the open lower end thereof, and secured in place by a cap N', which forms 10 the lower end of the said receptacle. The gas generated passes directly into a suitable burner O, located within the center of a reflector P of any approved construction.

I would have it understood that in carrying 15 out my invention I do not limit myself to the exact details of construction herein shown and described, but hold myself at liberty to make such variations therefrom as fairly fall within the spirit and scope of my invention.

20 Having fully described my invention, what I claim as new, and desire to secure by Letters Patent, is—

1. In an acetylene-gas bicycle-lamp, the combination with the water - tank thereof 25 formed in its top with a filler-opening, of a filler-cap, a swinging arm carrying the said

cap and swiveled centrally above the top of the said tank, a spring carried by and coacting with the said arm to hold it in its closed position, and a cam located upon the top of 30 the tank and coacting with the spring to place the same under tension.

2. In an acetylene-gas bicycle-lamp, the combination with a water-tank formed in its top with a filler-opening, of a hub mounted 35 in the center of the top of the said tank, an arm having swinging and rocking or tilting movement upon the said hub, and provided at one end with a spring and at the other end with a finger-piece, a button secured to the 40 said arm near its finger-piece, an elastic filler-cap secured to the said button and larger in diameter than the same, and a cam mounted upon the top of the said tank for coaction with the said spring. 45

In testimony whereof I have signed this specification in the presence of two subscribing witnesses.

WILLIAM A. PENFIELD.
